UNITED STATES PATENT OFFICE.

LEONADUS C. PORTERFIELD, OF ST. LOUIS, MISSOURI.

WASHING MACHINE.

Application filed October 24, 1921. Serial No. 509,821.

To all whom it may concern:

Be it known that I, LEONADUS C. PORTERFIELD, a citizen of the United States, and resident of the city of St. Louis and State of Missouri, have invented certain new and useful Improvements in Washing Machines, of which the following is a specification containing a full, clear, and exact description, reference being had to the accompanying drawings, forming a part hereof.

My invention relates to improvements in washing machines, and has for its primary object a washing machine having an oscillating scrubber or rubbing head which is adjustably secured in the lid of the machine, so that the same can be lifted from the tub simultaneously with the lid and which adapts itself automatically to various quantities of wash.

A further object is to construct a washing machine having an adjustable oscillating rubbing head mounted in the lid of the tub and a power-driven wringer secured to the tub. The whole being so arranged that the scrubbing head and wringer may be operated independently of each other or simultaneously.

In the drawings,

Fig. 1 is a side elevation of my machine, 30 viewing the same from the power side.

Fig. 2 a similar view of the other side.

Fig. 3 a rear elevation.

Fig. 4 a vertical section taken on the line 4-4 of Fig. 3.

Fig. 5 a fragmental view showing the manner of absorbing the shock when the crank arm is passing over center.

Fig. 6 a fragmental view of the rocking arm, showing the manner of securing it to 40 the scrubber head shaft.

Fig. 7 an enlarged fragmental view of one side of the top, showing the manner in which the scrubber head shaft bearings are mounted.

In the construction of my device, I employ a tub 8 which is substantially semi-cylindrical, and has formed integral therewith a projection 9. To the tub 8 is hingedly secured a lid 10 having sides 11. These sides 50 are provided with downwardly extending portions 12 which fit in the recesses 13 formed in the sides 14 of the tub. The downwardly extending portions 12 are provided with a slot 15 in which journal boxes 16 are slidably mounted. The journal boxes 55 are held within the slots by means of a strip

17 which is secured to the sides and which prevent the boxes 16 from coming out of the slot. Journaled in the boxes 16 is a shaft 18 to which a scrubber head 19 is secured. This scrubber head is semi-cylindrical in form and has sides 20 which are secured together by means of triangular strips 21. The bottom 22 of the tub 8 is provided with similar strips 23. The strips 21 and 23 performing the rubbing of the clothes when the head 19 is oscillated. Secured to both sides of the tub are legs 24 between which a shelf 25 is secured and on this shelf is mounted a driving device 26 which is preferably an electric motor, although various other devices may be used. Secured to the back of the tub are bearings 27 in which a split shaft 28 is mounted. The shaft 28 being provided with a dental clutch 29 which is operated by a lever 30, so that although the power device is operating, the operation of the scrubber head can be discontinued. On one end of the shaft 28 is mounted a spur gear 31 which meshes with a spur gear 32, secured on a shaft 33. On the shaft 33 is mounted a pulley 34 over which a belt 35 passes for communicating the power from the power device. On the shaft 33 is also mounted a bevel gear 36 which meshes with the bevel gear 37 mounted on one end of a shaft 38. This shaft is supported by bearings 39 secured to the side of the tub. Slidably mounted on the opposite end of the shaft 38 and rotatable therewith is a double bevel gear 40 which is operated by a lever 41 and which is so arranged as to mesh with the bevel gear 42 for placing the wringer 43 in operation. By means of this bevel gear it is possible to run the wringer in either direction, that is, to wring the clothes either from the machine or into it. Secured to the end of the shaft 28 opposite the gear 31 is a crank arm 44. Its free end being pivotally attached to one end of a connecting rod 45. The other end of this connecting rod being attached to the rocking arm 46. This rocking arm is provided on its upper end with a recess 47 which is preferably rectangular so as to receive the end of the shaft 18. After the recess of the rocking arm 46 has been placed over the shaft 18 a pivoted plate 48 is secured in place by means of a thumb screw and nut 49, as illustrated in Fig. 5. Secured to the shaft 28 is a double arm casting 50. This casting is adapted to revolve with

the shaft 28 and during its revolution, its ends come in contact with a coil spring 51 which is secured to the side of the tub by means of a socket 52. These arms extend 5 in the same direction as the crank arm, (see Figs. 2 and 5,) and are for the purpose of absorbing or reducing the shock as the crank and connecting rod pass over center, and thereby reduce the sudden jerk on the 10 clothes being washed to the reversing of the oscillation on the scrubber head.

Adjacent the free end of the lid 10 and extending entirely across the tub is a board 53. Its lower edge being raised some distance 15 above the floor of the tub, leaving a space 54 so that water from the clothes can flow back into the tub.

The operation of my device is as follows:

The rocking arm is first disconnected from 20 the shaft 18 and the lid 10 is raised. This carries with it the scrubber head 19 so that free access can be had to the tub. The desired amount of water placed in the tub, the wash then placed in, and the lid lowered, 25 and due to the presence of the slots 15 in the sides of the lid, the head will automatically adjust itself to the amount of clothes contained in the tub. The rocking arm is then again connected to the shaft 18 and the power device 26 started. This starting of 30 the power device will only rotate a portion of the shaft 28 until the lever 30 is moved so as to bring the dental clutch into engagement. The rotary movement of the shaft 35 28 is then communicated to the scrubber head 19 by means of the crank arm and rocking arm where it is reduced to an oscillating rocking movement.

When it is desired to remove the clothes from the tub, the dental clutch 29 is first disconnected, stopping the movement of the rubbing head. The rocking arm is then disengaged from the shaft 18 and the lid raised, carrying with it the rubbing head. The lever 41 is then operated so that one side 45 of the double bevel gear 40 engages with the bevel gear 42, thus placing the wringer in operation and the clothes then passed through the wringer. The water which is squeezed out of the clothes by the wringer returns to 50 the tub through the passage 54. It is also possible by reversing the direction of the wringer to take the clothes out of the soaking water and wring them so that they will pass directly into the tub 8, where they are 55 washed.

Having fully described my invention, what I claim is:

A washing machine comprising a tub, a lid provided with vertical slots in its side 60 walls hingedly secured to said tub, bearings slidably mounted in said slots, means carried by the lid for retaining the bearings in said slots when the lid is elevated; a rubbing head mounted in said bearings, a power 65 driven mechanism for oscillating said rubbing head, means for connecting and disconnecting the power driven mechanism from said rubbing head, and a shock absorber mounted on the tub for taking up 70 the jar of the scrubbing head at the end of each oscillation thereof.

In testimony whereof, I have signed my name to this specification.

LEONADUS C. PORTERFIELD.
